UNITED STATES PATENT OFFICE.

HERMAN S. HEICHERT, OF PITTSBURG, PENNSYLVANIA.

APPARATUS FOR TEEMING METAL.

No. 817,063.

Specification of Letters Patent.

Patented April 3, 1906.

Application filed July 24, 1905. Serial No. 271,084.

To all whom it may concern:

Be it known that I, HERMAN S. HEICHERT, a citizen of the United States, residing at Pittsburg, in the county of Allegheny and 5 State of Pennsylvania, have invented or discovered certain new and useful Improvements in Apparatus for Teeming Metal, of which improvements the following is a specification.

Considerable difficulty is experienced in 10 pouring metal from ladles in insuring the deposition of the metal at a given point or along a given line by reason of the movement of the ladle lip or edge over which the metal flows from one vertical plane to another while the 15 ladle is being turned on its pivotal axis. As a ladle is being tipped its pouring lip or edge, passing through an arc of a circle, will move away from a vertical plane passing through the pivotal center of the ladle until such lip is 20 in a horizontal plane through such pivotal center. After the lip or edge has reached such horizontal plane a further turning movement of the ladle will cause the lip or edge to move toward the vertical plane passing 25 through the center of movement of the ladle. In practice it is customary to endeavor to compensate for this in-and-out movement of the pouring lip or edge by regulating the flow of metal over the lip or edge by changing 30 the rate of tipping movement of the ladle. This method is, however, uncertain and unsatisfactory, especially when comparatively little metal remains in the ladle and the head of metal is not sufficient to produce a rate of 35 flow which will compensate for the inward movement of the pouring lip or edge, and consequently the last portions discharged from the ladle will be deposited back from the given point or line.

40 The invention described herein has for its object a construction and combination of elements whereby the pouring lip or edge can be caused to move during the tipping of the ladle in a vertical plane or a curved plane and 45 to have a position at the end of the pouring movement directly under its position at the beginning of the pouring movement or a position outside or inside of a vertical plane passing through the lip at the beginning of 50 the pouring movement.

The invention is hereinafter more fully described and claimed.

In the accompanying drawings, forming a part of this specification, Figure 1 is a side 55 elevation of my improved ladle-manipulating mechanism shown in connection with a travel-

ing crane and a bed and roller for spreading glass. Fig. 2 is a front elevation of the same, the table and roller being omitted. Fig. 3 is a detail view of the controlling-lever, and 60 Figs. 4, 5, and 6 are diagrammatic views illustrating some of the movements that can be imparted to the ladle.

In the practice of my invention it is preferred that the ladle and its manipulating mechanism, to be hereinafter described, should be carried by an overhead crane, although any other suitable form of support may be employed. As shown in the drawings, bridge 1 of the crane is provided with 65 suitable guide-rails for the wheels of a trolley, to which is secured a framework having guide-arms 2 for the lifting-head 3, which is adapted to be raised and lowered by means of a drum 4, carried by the trolley and preferably operated by an electric motor 5, the lifting-head being connected to a wire rope passing around the drum. The lifting-head 3 is provided with bearings 7 for the reception of the journal-pins 8, from which depend 70 the suspensory bars or rods 9, said bars being provided with eyes at their lower ends for the reception of the trunnions 10 of the yoke 11, engaging the ladle 12. The trunnions are provided with crank-arms 13, which are 75 connected by pitmen 14 to crank-arms 15 on a shaft 16, which is adapted to be rotated through suitable gearing by the motor 17. By the rotation of the shaft 16 the yoke 11 and ladle 12 will be tipped, the 80 trunnions of the yoke rotating in the bearings at the lower ends of the suspensory bars or rods 9. When shifted by the mechanism thus far described, the pouring-lip *a* of the ladle will pass through an arc *b*, as shown in Fig. 1, 85 and it will be observed that the lip *a* will gradually approach a vertical plane tangential to the spreading-roller 18 as the lip moves from normal position to a horizontal plane passing through the axis of the trunnion 10. 90 As the pouring-lip moves on downward it will gradually recede from the roller 18. During the first portion of the movement of the ladle the tipping movement can be so regulated that the metal, as glass, will be deposited immediately in front of the roller; but as the 95 lip moves from the horizontal plane passing through the trunnions the metal will be deposited farther away and spread out along the table in front of the roll. In order to 100 prevent this spreading out, suitable means are provided whereby the ladle may be so

shifted independent of its rotation on the axes of the trunnions that the pouring lip or edge *a* will at the end of the tipping movement be not farther away from the vertical plane tangential to the roller than at the beginning of the movement, but by preference will be closer to such tangential plane at the end of the tipping movement, so that although the rate of flow of metal from the ladle will be slower during the latter portion of the tipping movement the metal will be deposited in the same relation to the roller as at the beginning of the tipping movement. A convenient means for effecting this shifting of the ladle consists of a lever 20, having its fulcrum or pivot pin on the supporting bars or rods 9. One end of these levers is pivotally connected to the pitmen 14, while the portion of the lever on the opposite side of the pivotal centers is provided with means for engaging with guiding members, which in the present instance are formed by channel-bars 21, secured to the frame depending from the trolley. The levers are provided with pins or rollers 22, moving along these channel-bars as the levers are shifted by the rotation of the shaft 16.

By reference to Figs. 1, 4, 5, and 6 it will be seen that by reason of the engagement of the pins or rollers 22 with the channel-bars the suspending-bars 9, and with them the ladle, will be shifted to the left as the pitmen are raised, turning the levers 20 on their pivots. By suitably adjusting the length of the lever from its pivot center to the point at which the pins or rollers are secured and also by adjusting the angularity of these portions of the levers to the portions between the pivots and the connections of the levers to the pitmen any desired back-and-forth swing of the ladle during its tipping movement can be produced. It is preferred that the levers 22 should be made in sections, so that the portion thereof extending toward the channel-bars can be adjusted in angular relation to the other portions of the levers. In the construction shown the levers consist of two sections 20 and 20^a, the portion 20 being provided with a curved slot and the portion 20^a being adapted to swing about the pivot-pin as its center and be secured to the part 22 by a bolt passing through the slot. The portions 20^a, with the levers, are also slotted longitudinally, so that the pins or rollers in engagement with the channel-guides may be adjusted to different distances from the pivotal centers of the levers. The channel-bars, which serve as guides, are also adjustably mounted, so that when in normal position the ladle may hang naturally from its supporting shafts or trunnions 8, as shown in Fig. 1.

In Fig. 4 is diagrammatically represented the movements of the ladle when the pouring lip or edge is to move in a vertical straight line. It will be observed that the roller or

pin on the lever traveling along the guideway is in a line when the parts are in normal position, passing through the center of the journals 8 and the pouring lip or edge *a*. If, however, the point *b*, representing the pins or rollers on the levers, lies outside of a line from the axes of the journals 8 and the pouring-lip *a*, the latter will move in a plane having a curvature opposite that which the lip or edge *a* would have if the ladle should turn on its trunnions without any shifting thereof. If the point *b* lies inside of the line from the axes of the journals 8 to the point *a*, the latter will move through a plane of a reverse curvature of that shown in Figs. 5 and 6.

It will be seen that in all cases during the first part of the tipping movement of the ladle, when the point *a* would be normally traveling away from a vertical plane passing through the axes of the trunnions, then the ladle is shifted to the left an amount equal to the travel under normal conditions of the point *a* from said plane and that during the latter portion of the tipping movement the ladle will be moved in the opposite direction, so as to again compensate for what would be the normal movement of the lip *a* during the latter portion of the tipping movement.

In Fig. 5 I have diagrammatically shown an arrangement in which the pouring-lip *a* will move in the direction of the point or line where the metal is to be deposited and that at the end of the pouring movement the lip *a* will be a considerable distance to the right of a vertical plane passing through the lip at the beginning of the pouring movement. In Fig. 6 is shown an arrangement in which the lip *a* will be at the end of the pouring movement, to the left of a vertical plane passing through the lip or edge at the beginning of the pouring movement. The lip moves through a curved plane in passing between these two positions.

It will be readily understood by those skilled in the art that in the practice of my invention the position of the ladle is automatically adjusted, so that the metal will be always deposited when the ladle is tipped uniformly and at a rate proportional to the head of metal in the ladle at the same point or line during the entire pouring operation.

My improvement is especially applicable for use in connection with the teeming of glass onto a bed or table in the manufacture of sheet and wire glass, where it is desired that the metal shall be evenly distributed along in front of the spreading-roller in a line parallel or approximately parallel to the axis of the roller and should not be spread out irregularly along the table in front of the roller.

I claim herein as my invention—

1. In an apparatus for teeming metal, a ladle provided with suitable trunnions mounted on and in combination with mechanism for turning the ladle, and means operative by

the turning mechanism for shifting the ladle during the turning movement.

2. In an apparatus for teeming metal, the combination of a trunnion-supported ladle, mechanism for turning the ladle and means for so shifting the ladle that the final position of the pouring lip or edge will be at or forward of the rear of a vertical plane passing through the lip or edge in its initial position.
3. In an apparatus for teeming metal, the combination of a supporting-head, rods pivotally connected to the head, a ladle pivotally mounted on the rods, means for turning the ladle and mechanism operated by the turning means for swinging the suspensory-
rods and ladle.
4. In an apparatus for teeming metal, the combination of suspensory-rods, a ladle pivotally mounted on said rods, ladle-turning pitmen and means operated by said pitmen for shifting the ladle during its turning movement.
5. In an apparatus for teeming metal, the combination of suspensory-rods, a ladle pivotally mounted on the rods, ladle-turning pitmen, a lever pivotally connected to the suspensory-rod and the pitmen, a guide and a projection from the lever and engaging the guide.
6. In an apparatus for teeming metal, the combination of suspensory-rods, a ladle piv-

otally mounted on said rods, ladle-turning pitmen, a guide, a lever pivotally connected to the rod and pitmen and provided with means for engaging the guide.

35

7. In an apparatus for teeming metal, the combination of suspensory-rods, a ladle pivotally mounted on said rods, ladle-turning pitmen, a guide, levers pivotally connected to the rods and pitmen provided with an adjustable section and means on the adjustable section for engaging the guide.

40

8. In an apparatus for teeming metal, the combination of suspensory-rods, a ladle pivotally mounted on the rods, ladle-turning pitmen, adjustably-mounted guides, levers pivotally connected to the rods and pitmen and provided with adjustable means for engaging the guides.

45

9. In an apparatus for teeming metal, the combination of a pivotally-mounted ladle, mechanism for turning the ladle and means for shifting the ladle back and forth while turning without reversing the turning movement.

50

In testimony whereof I have hereunto set my hand.

HERMAN S. HEICHERT.
